UNITED STATES PATENT OFFICE.

LOUIS BENNET HALL, OF LONDON, ENGLAND.

FUEL-SUPPLY DEVICE FOR INTERNAL-COMBUSTION ENGINES.

1,263,886.

Specification of Letters Patent. Patented Apr. 23, 1918.

Application filed December 1, 1916. Serial No. 134,238.

To all whom it may concern:

Be it known that I, LOUIS BENNET HALL, a subject of the King of England, residing in London, England, have invented certain new and useful Improvements in Fuel-Supply Devices for Internal-Combustion Engines, of which the following is a specification.

This invention relates to improvements in fuel supply devices for internal combustion engines of the type in which liquid is pumped into the cylinder of the engine or a fuel pipe leading thereto.

The object of my invention is to provide a cheap and efficient device of this character in which the amount of liquid fuel pumped to the engine is controlled by the weight of the fuel passing to the engine, so that the proper mixture for forming an explosive charge is supplied thereto. I accomplish this by providing a pulsator for actuating the liquid fuel pump, which pulsator is actuated by the engine to be supplied, and I vary the stroke of the pump by connecting the pulsator with the fuel supply for the engine so that the pressure in the pulsator will vary in accordance with the amount of fuel passing to the engine whereby the proper amount of liquid will be fed to the engine for each charge.

The precise nature of my invention will be best understood by reference to the accompanying drawings described below, in which I have shown one form of my device, it being understood, however, that various changes may be made in the details of construction of the device without varying from the spirit and scope of my invention, as defined in the appended claims.

40 The mechanical construction of the device may be considerably varied. One example is illustrated in the accompanying drawings wherein—

Figure 1 is a longitudinal central section of one construction according to the present invention, and

Figs. 2 and 3 are constructions of the pulsator alternative to the construction thereof comprised in Fig. 1.

50 Like letters indicate like parts throughout the drawings.

With reference first to Fig. 1, a fuel pump FP is provided having valves IV and OV for the inlet and outlet of the petrol or paraffin or other liquid fuel. The outlet-valve is in a fuel delivery passage com-

municating with the combustion-chamber of the engine in any convenient or usual manner. The fuel-pump is provided with a ram R which reciprocates in the pump-body and draws the fuel from any suitable source of supply through the inlet-valve IV and expels it through the outlet-valve OV, to the engine. Outside the pump-body the ram or slider carries a roller R¹ through which it is driven. The roller engages one arm L¹ of a forked swinging lever L¹ L², pivoted by a fulcrum F between its ends, upon the end of an adjusting-lever AL. The other arm L² of the lever is likewise forked and engages a roller R² which is carried upon the reciprocating pump-operating piston POP. This piston slides to and fro in a cylinder C and acts against a spiral spring SP in compression between the piston and the wall of the box or casing K in which most of the apparatus is contained and which can be charged with a lubricant. By moving up or down the adjusting lever AL which carries the forked swinging lever L¹ L², the virtual length of one of the arms L¹ or L² may be increased, and that of the other reduced, so that the amount of stroke imparted to the ram R of the fuel-pump FP for a given movement of the pump-operating piston POP can be varied as may be desired.

The pulsator comprises a cylinder PC in which the pulsator piston PP works, the latter being driven by a crank and connecting rod from a shaft S geared to the engine. The pulsator-cylinder PC is provided with an annular port A at such a point that this port is just uncovered by the piston at the bottom of the stroke. To this annular port leads a pipe P from, say, the inlet-conduit of the internal combustion engine (by way if desired of an equalizing chamber) at a point between the throttle-valve and the engine-cylinders. In order to minimize the interchange of gases between the pulsator and engine, the periodic connection of the pulsator to engine should be so limited in time that the change, if any, of pulsator volume occurring during their connection should be as small as is practicable; this is the reason for arranging that the connection at the port A should occur in the pulsator illustrated when the pulsator-piston is at or near the end of its outward stroke.

The upper end of the pulsator-cylinder is connected through a pipe Q without valves

direct to the interior of the cylinder C in which the pump-operating piston POP works.

In operation, the pulsator-piston PP commences its upward stroke with a charge of air at the same pressure as obtains in the engine gas-inlet and inside the casing K at the moment, and compresses this during the up-stroke to a corresponding pressure which, 10 acting on the pump-operating piston POP, forces it to move in its cylinder against the resistance of the spring SP through a distance dependent upon the final amount of compression in the column in Q between the 15 pulsator and the pump-operating piston and simultaneously the ram R of the fuel-pump FP is operated by the lever L¹ L² to a corresponding degree to force out a proportionate charge of liquid fuel for the engine 20 through the outlet valve OV. On the return or downward stroke of the pulsator, the same column will be reexpanded and the fuel-pump will make its return stroke assisted by the spring SP which the pump-operating piston previously compressed. 25 When next the pulsator-piston is at the bottom of its stroke a small flow of air will take place either inward or outward from the annular port A, so that the contents of 30 the pulsator-cylinder change slightly in accordance with the change, if any, which may have occurred in the conditions in the pipe P leading from the engine, and again the fuel-pump will be given a stroke accordingly. 35

In the construction of pulsator-cylinder illustrated in Fig. 2, a screwed plug AP is provided to constitute an adjustable cylinder-end which can be screwed in or out to 40 vary the clearance-space in the pulsator-cylinder, and thus alter the compression-ratio of the pulsator. A lock-nut LN is provided to keep this adjustable cylinder-end fluid-tight in its place after adjustment.

45 In the construction of pulsator illustrated in Fig. 3 the amount of clearance in the pulsator-cylinder can easily be adjusted while the pulsator is running, for the cylinder-end is continued downward to form a sleeve 50 SL in which the pulsator-piston works; a rod M is extended upwardly from it through a screw adjusting-device of a well-known type by which the sleeve SL and with it the cylinder-head can be moved nearer to or farther from the unaltering upward limit of 55 stroke of the pulsator-piston, to vary the clearance.

In the construction illustrated in Fig. 3, there must be a mechanically-operated valve 60 V operated either from the engine or from the pulsator crank-shaft to open at the proper time and for the proper period the connection P between the pulsator and the engine-cylinder or other source of supply.

65 The timing of the valve V should be such

that the pipe P is not put into communication with the pulsator cylinder until the pulsator piston is at or near the end of its down-stroke; the piston co-operates with a port that may happen to be shifted to different positions by movement of the sleeve SL and therefore piston and port are not used to effect the timing in this construction. 70

In both these cases the cylinder-heads being movable the pipe-connections leading to them must be flexible. 75

By variation of the clearance-spaces of the pulsator the stroke of the fuel-pump may be adjusted into the desired relationship with the compression-pressure obtained in the pulsator-cylinder, in which case the adjustment of the position of the fulcrum F in Fig. 1 capable of effecting a like result can be dispensed with. Or the adjustable 80 fulcrum and the adjustability of the compression-spaces may both be employed. 85

The box or casing K should be air-tight, and there should be a pipe-connection EP between the pipe P and the inside of the 90 casing K to equilibrate the different pressures which may exist from time to time in the pipe P with the pressure inside the casing, that is to say with the fluid pressure acting against the right-hand end or outer 95 face of the pump-operating piston. These pressures will nearly always differ from the pressure of the external air. If the pump-operating piston be thus equilibrated, and pressure variations external to the apparatus be excluded, the final absolute 100 pressures of compression in the pulsator, less the fluid pressure in the casing, become what may be termed the final "gage" pressures for the pulsator. These final "gage" 105 pressures thus arrived at are the effective pressures by which the range through which the spring SP is compressed for each compression-stroke of the pulsator is determined, and the spring, actuated by pressures remaining after the piston POP has been equilibrated for its admission or initial "atmospheric" pressure in the manner above described, will be found to be compressed 110 in length in each action of the pulsator by 115 reductions varying, not in a ratio which is difficult to deal with mechanically, but in a simple ratio, namely, the same ratio as that in which the absolute admission-pressures to the pulsator vary. That is to say, 120 if the pulsator takes in a sample of air at a certain absolute admission-pressure (which also is the pressure in the casing K) and compresses it to 30 lbs. "gage" or effective pressure with a resulting reduction of the 125 length of the spring by $\frac{1}{8}$ of an inch, and a later stroke of the pulsator takes in a sample of air at double the absolute admission-pressure aforesaid (which shall also be the pressure in the casing K) and com- 130

presses it into the same final volume as that of the other sample there will be a final "gage" or effective pressure, arrived at in the manner above described, of 60 lbs. to the square inch, and a consequent reduction of the length of the spring by $\frac{1}{4}$ of an inch.

It should be noted that the range of pressures in the pulsator may be designed to be very much less than in the compression-
10 stroke of the engine-cylinder, and moreover that as in the pulsator the same air, with very small differences, is first compressed adiabatically and then expanded adiabatically, there is no tendency to continual increase of heat in the apparatus, for the mean temperature in the series of strokes of the pulsator is constant or very nearly so.

In the foregoing description I have de-
20 scribed an apparatus to be used in connection with a single cylinder engine, but it will be readily understood by those familiar with the art that my invention is adapted to be used in connection with a multi-cylinder
25 engine.

It will be seen that as the pulsator compresses and re-compresses continually, in the example illustrated, the same column of air, or as at any rate the end of the column nearest the pump-operating piston POP is always of the same air, there is no rush of heated air from the engine to the fuel-supply device, but only an oscillatory movement of the said column. Further, by connecting the pulsator to the suction-pipe or inlet-pipe of the engine (or to any part of the installation in which air representative of the air-charge in each cylinder at the commencement of compression therein exists—or even to the external atmosphere if the running conditions make the external atmosphere "representative" in the sense just previously indicated) instead of to the cylinder compression-space, the slight inter-
40 change of air between the pulsator and the engine which occurs when the position of the throttle-valve is changed, can only introduce cold, or nearly cold, inlet-air to the pulsator. But instead of sampling the air from the inlet-conduit, the air in the cylinder prior to compression or even during compression could be sampled, and the pulsator-pressure equalized therewith at the commencement of the pulsator-stroke and raised later on in
55 that stroke.

What I claim as my invention and desire to secure by Letters Patent is:—

1. A fuel-supply device for internal combustion engines, comprising a pump for de-
60 livering liquid, a pulsator, means for actu-
ating the pulsator in timed relation to the engine to be supplied with fuel, pump actuating means connected to the pulsator, and means controlled by the pressure of the
65 fuel passing to the engine for varying the

movement of the pump actuating means, substantially as described.

2. A fuel-supply device for internal combustion engines, comprising a pump having a piston for delivering liquid fuel to the engine to be supplied, a pulsator having a cylinder and a piston therein, a crank shaft for actuating said piston, means for actuating said crank shaft in timed relation to said engine, a motor cylinder, a piston
70 therein, actuating connections between said piston and the pump piston for actuating the pump piston, a pipe connected to the pulsator cylinder and the motor cylinder for delivering pressure to the motor cylinder
75 for actuating the motor piston, a connection leading from the pulsator cylinder to the intake for the engine, and a port communicating with said connection and the pulsator cylinder arranged to be opened
80 near the end of the stroke of the pulsator piston, in order to equalize the pressure in the pulsator cylinder and the pressure in said connection, substantially as described.

3. A fuel-supply device for internal combustion engines, comprising a pump having a piston for delivering liquid fuel to the engine to be supplied, a pulsator having a cylinder and a piston therein, a crank shaft for actuating said piston, a motor cylinder, a piston therein, actuating connections between said piston and the pump piston for actuating the pump piston, a pipe connected to the pulsator cylinder and the motor cylinder for delivering pressure to the motor cylinder
90 for actuating the motor piston in one direction, a spring for moving said motor piston in the reverse direction, a connection leading from the pulsator cylinder to the intake for the engine, and a port
95 communicating with said connection and the pulsator cylinder arranged to be opened near the end of the stroke of the pulsator piston, in order to equalize the pressure in the pulsator cylinder and the pressure in
100 said connection, substantially as described.

4. A fuel-supply device for internal combustion engines, comprising a pump having a piston for delivering liquid fuel to the engine to be supplied, a pulsator having a cylinder and a piston therein, a crank shaft for actuating said piston, means for actuating said crank shaft in timed relation to said engine, a motor cylinder, a piston therein, actuating connections between said piston and the pump piston for actuating the pump piston, a pipe connected to the pulsator cylinder and the motor cylinder for delivering pressure to the motor cylinder
115 for actuating the motor piston, a connection leading from the pulsator cylinder to the intake for the engine, a port communicating with said connection and the pulsator cylinder arranged to be opened near the end of the stroke of the pulsator piston, in order to
120 equalize the pressure in the pulsator cylinder and the pressure in said connection, substantially as described.

125

- equalize the pressure in the pulsator cylinder and the pressure in said connection, and means for varying the area of the pulsator cylinder, substantially as described.
5. A fuel-supply device for internal combustion engines, comprising a pump having a piston for delivering liquid fuel to the engine to be supplied, a pulsator having a cylinder and piston therein, an adjustable cylinder head in one end of said cylinder, means for adjusting said cylinder head, a motor cylinder, a piston therein, actuating connections between the motor piston and the pump piston, a pipe connected to one end 10 of the pulsator cylinder and one end of the motor cylinder for delivering pressure to the motor cylinder for actuating the motor piston in one direction, means for actuating the motor piston in the other direction,
- 15 10. a connection leading from the pulsator cylinder to the intake for the engine, a port communicating with said connection and the pulsator cylinder, and a valve in said port arranged to be opened near the end 20 of the expansion stroke of the pulsator piston to equalize the pressure in the pulsator cylinder and the pressure in said connection, substantially as described.
- 25 6. A fuel-supply device for internal combustion engines, comprising a pump cylinder having a piston therein for delivering liquid fuel, a pulsator having a cylinder and a piston therein, means for actuating said piston, a motor cylinder, a piston therein, adjustable actuating connections 30 between said piston and the pump piston for actuating the pump piston, said adjustable connections being arranged to vary the
- 35

throw of one piston relative to the throw of the other piston, a pipe connected to the 40 pulsator cylinder and the motor cylinder for delivering pressure to the motor cylinder for actuating the motor piston in one direction, and other means for actuating the piston in the other direction, substantially as described.

7. A fuel supply device for internal combustion engines, comprising a pump having a piston for delivering liquid fuel to the engine to be supplied, a pulsator having a cylinder and a piston therein, a motor cylinder, a piston therein, actuating connections between said piston and the pump piston for actuating the pump piston, a pipe 50 connected to the pulsator cylinder and one end of the motor cylinder for delivering pressure to the motor cylinder for actuating the motor piston in one direction, a spring for moving said motor piston in the reverse 55 direction, a pressure chamber at the other end of the motor cylinder, a connection leading from the pulsator cylinder to the intake for the engine, a port communicating with said connection and the pulsator cylinder arranged to be opened near the end 60 of the stroke of the pulsator piston in order to equalize the pressure in the pulsator cylinder and the pressure in said connection, and a connection leading from the pressure chamber to the intake for the engine to 70 equalize the pressure in the pressure chamber and the pulsator cylinder, substantially as described.

In testimony whereof I have signed my name to this specification.

LOUIS BENNET HALL.
